UNITED STATES PATENT OFFICE.

CAID H. PECK, OF WAVERLY, NEW YORK, ASSIGNOR TO INGERSOLL-RAND COMPANY,
OF JERSEY CITY, NEW JERSEY, A CORPORATION OF NEW JERSEY.

FLUID-OPERATED PERCUSSIVE TOOL.

1,122,630.

Specification of Letters Patent.

Patented Dec. 29, 1914.

Application filed April 28, 1914. Serial No. 834,887.

To all whom it may concern:

Be it known that I, CAID H. PECK, a citizen of the United States, residing at Waverly, in the county of Tioga and State 5 of New York, have invented a certain new and useful Improvement in Fluid-Operated Percussive Tools, of which the following is a specification.

This invention relates to pressure operated percussive tools and more particularly to tools of the so-called "valveless" type.

The object of this invention is to produce a tool of simple construction and one which has at the same time high power and low 15 consumption of operating fluid.

With this object in view a tool has been devised, a practical embodiment of which is shown in the accompanying drawing, in which,

20 Figures 1 and 2 show longitudinal sections through the tool cylinder with the piston in different positions.

The invention is shown as applied to a plug drill, which comprises a cylinder 1 of 25 constant diameter throughout its entire length, in which slides a piston 2. In the rearward portion of the piston 2 is a bore or elongated cavity 3 the rearward portion of which is of smaller diameter and cross sectional area than the forward portion. Projecting into the bore 3 is a fluid inlet plug 4, which has a head 5 fitting into the smaller diameter portion of the bore 3 and a neck 6 of smaller diameter and cross sectional area.

35 The plug 4 is tubular in shape forming a fluid inlet passage 7 whereby a constant pressure is maintained in the bore 3 during the operation of the tool. The lengths of the larger diameter portion of the bore 3 and of

40 the head 5 of inlet plug 4 are so calculated that the rear edge of the head 5 will pass into the larger portion of the bore 3 near the end of the rearward stroke of the piston, thus affording a passage for the actuating

45 fluid to the rear end of the cylinder. From the larger diameter portion of the bore 3 a port 8 opens to the surface of the piston, and from the front end of the cylinder a passage 9 extends rearwardly opening into the cylinder again at a point such that it registers with the port 8 near the forward end of the

50 piston stroke. Exhaust ports 10 and 11 are provided, respectively, for the front and rear ends of the cylinder and are positioned

to be uncovered near the end of the stroke in 55 each direction.

The operation of the tool will be evident from the above description. Fluid will be admitted constantly to the bore 3 through the passage 7 and exert a constant pressure 60 on the forward end of the bore 3. Fluid will also be admitted through the rear end of the cylinder for a short portion of the stroke when the head 5 of the inlet plug 4 has passed completely into the larger diameter 65 portion of the bore 3 as shown in Fig. 2. To drive the piston rearwardly fluid will be admitted from the bore 3 through the port 8 and passage 9 for a small portion of the rearward stroke while the port 8 and passage 70 9 register as shown in Fig. 1. The exhaust ports 10 and 11 alternatively exhaust the fluid from the intermittently supplied ends of the cylinder.

It is to be understood that the present 75 showing and description discloses only one specified modification of the invention and other forms and modifications are included in the spirit and scope of the invention as expressed in the claims.

80 What I claim is:—

1. In a fluid operated percussive tool, a cylinder, a piston having an elongated cavity in its rearward portion, an inlet plug, projecting into said cavity, having a passage 85 for conveying fluid to exert a constant pressure on the forward end of said cavity, and passages arranged to alternately admit fluid from said cavity to the ends of said cylinder and exhaust it therefrom. 90

2. In a fluid operated percussive tool, a cylinder of constant diameter, a piston having a bore in its rearward end, the rearward end of said bore being of smaller diameter, a fluid inlet tube projecting 95 into said bore said tube having a head fitting the smaller portion of the piston bore, and a neck of smaller diameter, a port from the larger portion of said bore to the surface of the piston, a passage from the forward end of the cylinder to the intermediate portion adapted to register with said piston port near the forward end of the piston stroke, and exhaust ports near the front and rear ends of the cylinder. 100

3. In a fluid operated percussive tool, a cylinder, a piston having an internal bore in its rearward portion, said bore being 105

smaller in cross sectional area at its rearward end, an inlet plug fitting into said bore and having a passage therethrough for conveying fluid constantly thereto, said plug 5 also having a head fitting said smaller portion of the piston bore, and a rearward portion of smaller cross sectional area than said head, a port leading from the larger part of the bore to the surface of said piston, a passage 10 leading from the forward end of the cylinder to a point positioned to register

with said piston port near the forward end of the piston stroke, and exhaust ports uncovered by the piston near the end of each stroke.

15

In testimony whereof, I have hereunto set my hand.

CAID H. PECK.
